PERMIT MAILING AND STAMPING MACHINE

Robert Severin Nilsson, Le Vesinet, France, assignor to Société Anonyme des Etablissements Cuttat, Rueil-Malmaison, France

Application July 30, 1935, Serial No. 33,883
In France August 4, 1934

2 Claims. (Cl. 101—368)

This invention relates to a permit mailing and stamping machine for letters, health insurance cards, recorded documents, and the like.

The invention has for its object to provide means to prevent improper use of the printing element of such machines either by fraudulently duplicating the printed mark by means of a carbon sheet or by making a plurality of impressions during one operation of the machine.

10 In the accompanying drawing wherein an approved embodiment of the invention is illustrated:

Fig. 1 is a side elevation, partly in section, of the invention.

15 Figs. 2, 3 and 4 are similar fragmentary views showing the parts of the printing element in different positions.

Referring to the drawing in detail the printing element designated at 65 is mounted for vertical 20 movement between a rear guide roller 81 and front guide rollers 79 and 80. The printing element is raised to inoperative position by means of a cam 69 secured to a shaft 64, the cam engaging a roller 67 carried by a yoke 66 fixed to 25 the printing element.

Fingers 167 are provided in the printing block 65. These fingers are in variable number, for instance they are two in number and are so arranged as to surround the value printed, or they 30 are three in number, one of the fingers being interposed between the digits representing francs and those representing centimes.

Each finger 167 is pivoted, at its upper end, on a lever 168 capable of rocking about a pin 35 169 carried by the printing block. For that purpose, the finger 167 carries a small pin 170 extending in an oblong opening 171 provided in lever 168, and the latter has a nose 172 capable of engaging with one of the two teeth 173 and 40 174 formed on a locking member 175.

The locking member 175 has an eye 176 through which it is mounted on a pin 177 carried by the printing block 65.

45 The locking member 175 has another set of teeth 178 and 179 with which can cooperate the nose 180 of a pawl 181 rockably mounted about a pin 182 carried by the printing block 65.

The lever 168 is constantly urged downwardly 50 by a spring 183; the lower part of the locking member 175 is attached to a spring 184, the other end of which is secured to the printing block 65; the spring 184 is disposed obliquely relatively to the vertical, so that it urges the locking member 175 both downwardly and towards the noses 172 55 and 180. A spring 185, wound about the pin 182,

urges the pawl 181 towards the locking member 175.

Abutment rods 186 and 187, rigid with frame members of the machine, in the position of rest of block 65 (which is the upper position), respectively hold the finger 167 in raised position and the member 175 in inoperative position. The finger 167 is lifted and offset relatively to the impression face 65a of the stamping element, by the rod 186 acting on lever 168. The rod 187, 10 by acting on locking member 175 and pawl 181, moves these two members apart and the locking member 175 is moved out of engagement with the nose 172. For this position, the pin 177 is in contact with the upper part of eye 176. 15

When, during the actuation of the machine, block 65 begins to move down, the abutments 186 and 187 are disengaged; the locking member 175 comes in a position in which its edge carrying the teeth is approximately vertical, owing to the 20 action of spring 184. Under the action of spring 185, the nose 180 of pawl 181 engages with the upper tooth 178. Under the action of spring 183, the nose 172 of arm 168 engages with the upper tooth 173 and the finger 167 is thereby projected 25 outwardly relatively to the surface of the stamping element. The upper portion of the eye 176 is in contact with the pin 177 (Fig. 2).

The pressure due to the fall of the printing block on the document to be stamped or the 30 postage of which is to be prepaid is first exerted through fingers 167, thereby avoiding fraud by duplicating the printed mark with a carbon sheet because the document placed under the carbon sheet will bear the impression of the fingers 167 35 and thus reveal the fraud.

Under the action of this pressure, the fingers 167 enter within the printing block, causing lever 168 to rock about the pin 169. During this 40 rocking movement, the nose 172 lifts the locking member 175 to a corresponding extent and the nose 180 riding over the first tooth 178, engages with the lower tooth 179. In this position the lower part of eye 176 is in contact with the pin 177. The position shown is that of Fig. 3: it is 45 the printing position.

When the printing block begins to rise, the lever 168 rocks under the action of spring 183, thereby causing fingers 167 to project. During this rocking movement, the nose 172 of lever 168 50 engages with the lower tooth 174. Therefore, if after printing, it is attempted with fraudulent intent, to effect a new impression without restoring the printing block to its starting position, said printing block 65 would bear on the 55

document through the medium of fingers 167; these fingers 167 being in locked position: their pressure on the document would tend to lift the locking member 175. Upward movement of the member 175 is absolutely prevented, however, by the pin 177 abutting against the lower portion of the eye 176. In no case whatever can the stamping element then be brought into contact with a document placed underneath the same (Fig. 4).

10 By actuating the actuating cam 69, the printing block 65 is moved to its upper position for a new operation to be effected, and the rods 186 and 187 ensure unlocking.

15 18 What I claim as my invention and desire to secure by Letters Patent is:

1. In a permit mailing and stamping machine, a printing element having an impression face, means for raising and releasing said printing element whereby, during its fall, the impression is made, fingers movably mounted on said printing element, means for resiliently holding said fingers in a position projecting beyond said impression

face during the descent of the printing element, and means for locking said fingers in projecting position only during the ascent of said printing element.

2. In a permit mailing and stamping machine, a printing element having an impression face, means for raising and releasing said printing element whereby, during its fall, the impression is made, fingers movably mounted on said printing element, means for resiliently holding said fingers in a position projecting beyond said impression face during the descent of the printing element, a locking member mounted for axial movement in said printing element, groups of teeth formed at the opposite ends of said locking element, a toothed member cooperating with one group of teeth on the locking element to lock said fingers in projecting position only during ascent of said printing element, and a pawl cooperating with the other group of said teeth on said locking element. 10 15 20

ROBERT SEVERIN NILSSON.
